DESIGN FOR A DISPLAY HANGER OR SIMILAR ARTICLE

Sidney Ring, New York, N. Y.

Application June 1, 1936, Serial No. 62,941

Term of patent 3½ years

To all whom it may concern:

Be it known that I, Sidney Ring, a citizen of the United States, residing at New York city, in the county and State of New York, have invented a new, original, and ornamental Design for a Display Hanger or Similar Article, of which the following is a specification, reference being had to the accompanying drawing, forming a part thereof.

Fig. 1 is a front view of a display hanger showing my new design;

Fig. 2 is a side view thereof on a reduced scale;
Fig. 3 is a view similar to Fig. 1 on a reduced scale, illustrating the manner of using the hanger embodying the present design.

I claim:

The ornamental design for a display hanger or similar article substantially as shown and described.

In testimony whereof I have signed this specification.

SIDNEY RING.
